[52] U.S. Cl. D34/5; D6/566

[58] Field of Search D34/1, 5, 6; 248/95, 248/97, 98, 99, 100, 101; 220/908, 909, 404; D6/566

4,840,336 6/1989 Stroh et al. D34/5

Primary Examiner—Kay H. Chin
Attorney, Agent, or Firm—Leon Gilden

[57] CLAIM

The ornamental design for a bag holder, as shown and described.

DESCRIPTION

FIG. 1 is a front elevational view of the bag holder showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a top and front perspective view thereof, the broken lines are for illustrative purposes only and form no part of the claimed design.
